RESILIENT CALK FOR HORSESHOES

Carl G. Akerberg, Oshkosh, Wis., assignor to
Giant Grip Manufacturing Company, Osh-
kosh, Wis., a corporation of Wisconsin

Application April 19, 1934, Serial No. 721,386

3 Claims. (Cl. 168—41)

The present invention relates to improvements in padded horseshoe calks.

Where it is found necessary to employ horses for regular service over hard finished roads and city streets, some means in the horseshoe for absorbing road shock and eliminating noise is found to be desirable and practically essential. The problem has attained partial solution in the prior art through the medium of resilient calks 10 detachably secured to the under side of the horseshoe. Such calks have proven partially unsatisfactory, however, due to the rather hard and insufficiently resilient nature of the padding employed, and to the lack of strength and durability of the entire structure. Further, serious difficulties tantamount to failure have arisen, in most instances in the manner of securing the pads to the horseshoes.

Prior means, for fastening padded calks to 20 horseshoes, have consisted of metal inserts embedded in the pad portions of the calks and having integral extensions which are secured in the horseshoes. Failure has occurred consistently in most of such prior devices due to crushing or 25 spreading of the metal inserts when subjected to the heavy load imposed by the horse. Non-deformable inserts have been proposed but they have been too heavy and too difficult to bond securely and properly within the pad.

30 It is therefore a primary object of the present invention to provide a resilient horseshoe calk in which the metal insert is securely fastened in the resilient pad, and prevented from deforming.

35 Another object of the invention is to devise a detachable horseshoe calk member having one part thereof firmly and non-crushably anchored in a resilient pad, the other part forming an extension to mate with the horseshoe.

40 A further object of this invention resides in the provision of a horseshoe calk of maximum resilience and wherein a minimum amount of metal structure is employed.

45 A still further object of the invention is the provision of a detachable horseshoe calk in which the metal insert embodies means for very securely anchoring the insert to the resilient pad while simultaneously reinforcing said insert.

50 Another object of the present invention is to devise a horseshoe calk of maximum strength in the bond between the resilient pad and the metallic insert.

A still further object of my invention is the 55 provision of a horseshoe calk of great strength

and resilience which is yet simple and inexpensive to manufacture.

It is another object of my invention to devise a simple horseshoe calk insert which is so designed as to permit the satisfactory use of a pad of unusually great resilience.

With the above and other objects in view the detailed description will proceed, reference being made to the accompanying drawing in which like reference characters are employed to denote 10 like parts throughout the several views.

Figure 1 is a bottom plan view of a horseshoe provided with a detachable calk embodying the present invention.

Figure 2 is a partially fragmentary sectional view taken on the line 2—2 of Figure 1 and showing in elevation the metal insert embedded in the resilient pad.

Figure 3 is a view similar to Figure 2, but illustrated in complete section.

Figure 4 is a sectional view taken on the line 4—4 of Figure 1 and at right angles to the plane of Figure 3.

Figure 5 is a top plan view of the metal insert and its reinforcing means.

Figure 6 is a bottom plan view of the insert shown in Figure 5.

Referring now to Figure 1 of the drawing, reference numeral 11 designates a horseshoe of the conventional type having on its forward part spaced apertures 12 which are tapered upwardly and inwardly. The rear portion of the horseshoe is provided with similar apertures 13. A detailed disclosure of these apertures can be obtained by reference to Patent No. 1,875,405, granted September 6, 1932.

As illustrated, the forward openings 12 are adapted to receive individual conventional drive calks 14 of all-metal construction, but which may well take the form of special resilient calks (not shown), embodying the present invention if desired. The openings 13 in the heel of the horseshoe are adapted to receive a resilient bar pad, indicated generally at 16, which has been selected to illustrate the major part of my invention. 45 Various other types of pads are adapted to embody the invention.

The resilient bar pad or calk 16 comprises two symmetrical sections 17 and 18 which are joined by the bridge portion 19. Each of the sections 17 and 19 is firmly secured to the horseshoe 11 in a manner presently to be set forth.

With additional reference now to Figures 2-6 of the drawing, it will be seen that the calk 16 is constructed in general of two main parts, 55

namely: a resilient pad 21 and a plurality of metallic inserts 22 which will now be described in detail.

The pad 21, composed of resilient and shock absorbing material is for the purpose of dampening shocks and jars and absorbing other undue impacts which normally would be transmitted to the horse by means of the conventional metal shoe. I have found in practice that rubber serves as the best known material in forming the pad 21. I have found further that rubber of a hard or semi-hard nature is undesirable for several reasons, but that until the time of my improvement an undesirably hard rubber was the only kind that could find practical use.

One of the cardinal objections to the use of semi-hard rubber is its lack of sufficient resilience and its failure to properly absorb shock. As it is a primary purpose of my invention to devise a calk of maximum resilience and shock absorbing qualities, it will be apparent that the use of hard rubber in the construction would defeat the principal aim of the invention. Another serious objection to the use of hard rubber arises from its proclivity to chip and crack under pressure. This tendency has caused failure of previous calks due to the cracking of the rubber adjacent the metal insert and subsequent tearing loose of the insert from the pad. A semi-hard rubber further lacks the ground-gripping action or traction that can be obtained with a softer rubber, due to the fact that soft rubber may be deformed sufficiently in operation to spread the pad into substantially full and balanced engagement with uneven surfaces. The desirability of utilizing softer rubber may have been recognized heretofore, but to my knowledge no one has succeeded in devising an anchoring means or joint for securing such a pad firmly and permanently to the horseshoe. With my improved calk construction, however, I have found it feasible to use a grade of rubber which is much more soft and yielding than has heretofore been deemed possible, thus overcoming the serious faults above set forth.

The metallic inserts 22 function to secure the resilient pad 21 to the horseshoe 11. To this end each insert comprises a split flanged lower portion 23 and an upper extension 24, represented in the specific embodiment shown as being hollow in nature. Each extension 24 mates within a corresponding aperture 13 in the horseshoe heel to securely fasten the pad 16 with respect to the horseshoe.

The method of forming the metal inserts is of such nature as to provide an extremely simple and inexpensive process of manufacture. Each insert is stamped in one operation from a single metal blank. The forming dies press the central portion of the blank into the configuration shown by the extension 24 of Figures 2, 3 and 4. Simultaneously the end portions of the blank are pressed outwardly to form wing-shaped flanges as at 27 and 28 and are provided with holes 25 and 26 for a purpose that will presently become apparent.

Extending between wing flanges 27 and 28 of each insert and through holes 25 provided therein is a rivet 29. The head 31 of rivet 29 lies against the outside surface of the flange 28, while the swaged end 32 of the rivet bears against the exterior face of the flange 27. It will readily be seen that in this manner each rivet functions to prevent spreading of the flanges 27 and 28 with respect to each other and acts in effect as a tie rod between the said flanges. Each rivet further

acts as an additional anchoring means in the resilient pad as will presently be set forth.

As previously stated the flanges 27 and 28 of each insert 22 are embedded in the resilient pad 21. In the embedding operation the resilient material is allowed to flow up into the hollow extension 24 of the insert, thereby imparting added strength and durability to the said extension and to the joint. Further, the flow of resilient material into extension 24 strengthens the bond between the insert and the pad, thereby increasing the strength of the calk construction as a whole and diminishing the possibility of the metal insert tearing loose from the resilient pad.

As will be readily appreciated from an inspection of Figure 3 of the drawing, when the detachable calk is assembled with respect to a horseshoe, a severe load is imposed upon the metallic insert 22 due to the weight of the horse. In consequence a reactive stress of appreciable magnitude is developed in the metal insert and the tendency to strain or deform becomes very great. In prior inserts the deformation of the metallic inserts has been so great as to cause separation of the flanges 27 and 28 thereof, accompanied either by crushing of the whole insert or separation of the pad from the insert.

By means of my improved structure these defects have been obviated. The entire insert has been greatly strengthened and the bond between the metal and rubber made more secure due to the added anchoring action of the rivet embedded in the resilient pad.

The bond between the insert and the resilient pad is further strengthened by means of the holes 26 in the insert flanges into which the resilient material flows and gains an anchoring hold. Furthermore the flanges 27 and 28 of the insert always exert a maximum anchoring action in the resilient pad since under working loads the flanges have no tendency at all to contract but tend to spread apart as far as the limitations imposed by the rivet 29 will allow.

Another great advantage deriving from my improved construction resides in the fact that the inserts 22 may have but a shallow anchor in resilient pad 21 and still retain the strength of bond with the said resilient pad necessary under the most severe working conditions.

It will be readily appreciated that a shallow insert anchor increases the depth of resilient padding available for actual road wear. I have found in commercial use that the resilient pad may be worn down to within $\frac{1}{4}$ " of its bottom face and still give excellent results. It will thus be seen that my improved detachable calk construction affords a calk not only of increased strength and resilience but of longer life as well.

I have found it desirable in forming the inserts of the present invention to employ blanks of relatively thin metal. By using inserts which are formed from relatively thin metallic blanks, and which are anchored to only a shallow depth in the pad portion of the calk, an assembly comprising a minimum of metal and a maximum of padding is produced. It will be quite obvious that such an assembly is marked by a maximum of resilience, especially in view of the malleable nature of the small amount of metal which is employed. Further benefits resulting from the use of thin sheet metallic inserts reside in the consequent economies of manufacture and the decrease in weight of the calk assembly.

To summarize briefly, my invention provides a detachable horseshoe calk of increased strength,

greater durability, lighter weight, superior resiliency, and longer life than any heretofore produced; and therefore it will be apparent that the superior quality of service rendered by my improved calk, coupled with the greatly increased economies in manufacture and use of the same, constitute a distinct and important advance in the art.

As the present invention resides chiefly in an improved anchoring means and the better complete calks that can be produced as a result thereof, it is obvious that various other types of pads may be substituted for the illustrated flexible bar pad. For example, pads such as those disclosed in Patent No. 1,777,727 to Krug, et al., may be utilized, but in all of such instances, a rubber will be used that preferably is softer than has heretofore been considered practicable.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

30 What is claimed and desired to be secured by United States Letters Patent is:—

1. A horseshoe calk comprising a resilient pad member; a metallic insert having a hollow upper

extension for engagement with a horseshoe and lower flanged portions embedded in said pad and providing a concavity for receiving some of the resilient material of said pad; and means interconnecting and reinforcing said flanged portions and adapted to strengthen the bond between said pad and said flanged portions by retaining said pad material within said concavity.

2. A horseshoe calk comprising a resilient pad member; a metallic insert having a split upper extension for engagement with a horseshoe and lower winged anchoring portions bonded in said pad and providing a concavity for receiving some of the resilient material of said pad; and means interconnecting said winged portions and adapted to restrain said winged portions against relative displacement and to increase the strength of bond between said pad and said winged portions by retaining said pad material within said concavity.

3. A horseshoe calk comprising a relatively soft and unusually resilient pad member; a metallic insert having a recessed upper extension for engagement with a horseshoe and lower flared portions of relatively thin metal anchored in said pad and providing a concavity for receiving some of the resilient material of said pad; and means interconnecting and reinforcing said flared portions and serving to strengthen the anchorage of said flared portions in said pad by retaining said pad material within said concavity.
